CLAIM

The ornamental design for a medical device tray sealer having a tray burst testing system, as shown and described.

DESCRIPTION

FIG. 1 is a Front Perspective left view of a medical device tray sealer having a tray burst testing system, showing my new design;

FIG. 2 is a Front Perspective right view of the medical device tray sealer having a tray burst testing system of FIG. 1.

FIG. 3 is a Rear Perspective view of the medical device tray sealer having a tray burst testing system of FIG. 1, the right view being a mirror image of this view.

FIG. 4 is a front view of the medical device tray sealer having a tray burst testing system of FIGS. 1-3.

FIG. 5 is a back view thereof.

FIG. 6 is a left view thereof.

FIG. 7 is a right view thereof.

FIG. 8 is a top view thereof.

FIG. 9 is a bottom view thereof.

FIG. 10 is a front perspective left open tray view thereof; and,

FIG. 11 is a front perspective right open tray view thereof.

1 Claim, 8 Drawing Sheets
